UNITED STATES PATENT OFFICE.

DANIEL M. PFAUTZ, OF GERMANTOWN, PENNSYLVANIA.

FILTERING SYSTEM.

SPECIFICATION forming part of Letters Patent No. 791,647, dated June 6, 1905.

Application filed July 2, 1904. Serial No. 215,066.

To all whom it may concern:

Be it known that I, DANIEL M. PFAUTZ, a citizen of the United States, residing at Germantown, in the county of Philadelphia and State of Pennsylvania, have invented certain new and useful Improvements in Filtering Systems, of which the following is a specification.

My invention has relation to a filter especially adapted for the filtration of water under pressure and in mains; and in such connection it relates to the construction and arrangement of such a filter.

The nature and scope of my invention will be more fully understood from the following description, taken in connection with the accompanying drawings, forming part hereof, in which—

Figure 1 is a horizontal sectional view of a filtering apparatus embodying main features of my present invention. Fig. 2 is an enlarged vertical sectional view. Fig. 3 is an enlarged cross-sectional view taken on the line 4-4 of Fig. 1. Fig. 4 is a top or plan view of the lid or closure for the filter-compartments and of the locking mechanism therefor. Fig. 5 is an enlarged detail view of the locking-levers of Fig. 4; and Fig. 6 is a top or plan view, on a smaller scale, of the filtering apparatus.

Referring to the drawings, *a* represents the main water-distributing pipe, leading from a reservoir or other source of supply. (Not shown.) This pipe *a* branches, as at *a'*, and enters two water-tight casings *b* and *b'*. These casings *b* and *b'* constitute, respectively, the inclosure for separate filter apparatus, which, so far as arrangement and construction are concerned, are duplicates. In a casing *b* or *b'* are arranged a series of vertical filter-beds *d*. Each bed *d* consists of a box having front and rear faces of netting *d'* and filled with filtering material held down in the box by a heavy plate *d''*. The beds *d* are removable vertically from the casing and slide upon ribs *b''*, arranged on the sides of the casing. (See Fig. 1.) The sides of the box forming the bed are channeled, as at *d''*, to closely fit the ribs *b''*, and thus afford a liquid-tight joint between the casing and the sides of the bed *d*.

The bottom *d⁴* of each bed *d* rests upon a plate *b⁴* on the base of the casing *b* or *b'*, and this plate *b⁴* has a rib *b⁵* snugly fitting a corresponding depression *d⁵* in the bottom of the bed *d* to thus form between the base of a bed *a* and the base of the casing a liquid-tight joint. 55

Each box constituting the receptacle for the filtering material is provided with a lid *d⁶*, arranged to be bolted or otherwise secured down upon the casing and to be removed therefrom. Any form or means for fastening this lid *d⁶* down upon the casing and the filter-box may be used. The preferred form, however, is illustrated somewhat in detail in Figs. 4 and 5. This preferred form consists, essentially, of a screw-bolt *e*, traversing the lid *d⁶* and having a headed lower end resting upon the under surface of the lid. The bolt passes through a collar *e'*, which may be turned upon the bolt *e* to advance or retract the collar. On the collar *e'* loosely turns a sleeve *e''*, to which is pivoted a series of locking-arms *e³*. These arms *e³* pass through brackets *e⁴*, projecting from the top of the lid *d⁶*, and through keeper-plates *e⁵*, connected with the casing *b* or *b'*. These arms are adapted when the sleeve *e''* is turned by the handle *e'* in one direction to be projected outward to engage the said keeper-plates *e⁵*. 70 75 80 85 90 95 100 When turned in an opposite direction, the sleeve *e''* retracts the arms *e³* and draws the same out of the keeper-plates *e⁵*. When the arms *e³* are in the keeper-plates *e⁵* and the collar *e'* is turned by its handle *e'* to be advanced upon the bolt *e* toward the lid *d⁶*, then the inner ends of the arms *e³* are depressed and the outer ends raised against the keeper-plates *e⁵* to force the lid *d⁶* down upon the box or bed *d* and onto the casing *b* or *b'* by means of the brackets *e⁴*, so as to render a filter-bed *d* water-tight at its upper end and also to prevent the escape of water between the casing *b* or *b'* and the lid *d⁶*, as clearly illustrated in Fig. 2 of the drawings.

The beds *d* are arranged vertically in each of the filters *B* and *B'*. If the valves *B²*, *B³*, *B⁴*, and *B⁵*, arranged in the branch pipes *a'* and *a''*, are opened, the water coming from the main *a* must pass under pressure into a cham-

ber f of each of the filters B and B', in front of the first bed and under pressure through said bed into a succeeding chamber f , in front of the second bed d , and so on until the chamber f' in each filter is reached, from which the same by means of the branch pipes a^2 flows into a pipe a^3 for distribution. Thus in the instance shown where three filter-beds are used four chambers f are required, the first 5 chamber being in front of the first bed and the last chamber f' being to the rear of the last bed to constitute a reservoir for the purified water. The reservoir f' communicates by the pipe a^2 with the continuation a^3 of the 10 main a , as clearly illustrated in Figs. 1 and 6. The entire filtering apparatus is hence interposed directly in a main or water-distributing pipe and can be cut into or out of the main, as required, by means of the system of valves 15 illustrated in Figs. 1 or 6. Thus in Fig. 1 provision is made for cutting either of two adjacent filters B-B' into or out of the main. In this instance if the lower filter B' is to be cut out then a gate-valve B² on the branch 20 pipe a' is shut and a similar valve B³ on the pipe a^2 is closed. The water from the main a then passes only through the filter B. If the filter B is to be cut out and the filter B' only is to be used, then the valves B² B³ are 25 opened and similar valves B⁴ B⁵ are closed. In Fig. 6, however, provision is also made for cutting both filters B and B' out of the main. In this instance the main a is connected directly by a pipe a^{10} with its continuation a^3 , 30 and upon the pipe a^{10} is arranged a valve a^{11} , which is closed when either or both filters B and B' are in operation and is opened when both of said filters B-B' are cut out of the main. 35

40 When the beds of either filter B or B' are to be cleansed, the filter is cut out, as before described, and the bed or beds d removed from the apparatus. When the filters B and B' are to be flushed, then a system D of drainage-pipes from the bottom of the chambers f , f' is opened and the valve B³ or B⁵ on the branch pipe a^2 is closed. In this instance the beds d are removed from the casing prior to flushing. In front of each bed d and at the base of the 45 screen d' is arranged a tubular catch-pan g , having a slot or opening g' at its top adjacent to the bottom of the screen d' . One end of this tubular pan g is connected with the drainage-pipes D. As impurities gather on the 50 screen d' they fall into the pan g . To flush these pans g , water is diverted from a compartment or chamber f through the pan g and into the drainage-pipes D.

The weighted plates d^2 on the filtering material in the boxes d permit of the increase or decrease in bulk of the material within the boxes without impairing the efficiency of the material. The plates d^2 also prevent the fil-

ter material from being agitated by passage of water under pressure through the material. 65

Having thus described the nature and object of my invention, what I claim as new, and desire to secure by Letters Patent, is—

1. In a filtering apparatus, a casing, a wedge-shaped rib at the bottom of said casing, a filter-bed disposed in and removable from said casing and having its bottom indented to form a wedge-shaped groove adapted to fit the rib at the bottom of said casing. 70

2. In a filtering apparatus, a casing, flat ribs arranged on either side of the casing, a wedge-shaped rib arranged on the base of the casing, and a filter-bed having its sides and bottom indented complementally to the shape of the side and bottom ribs of the casing, said bed 80 arranged vertically in the casing and resting upon the bottom rib of said casing. 75

3. In a filtering apparatus, a casing interposed in a water-distributing pipe or main, a series of vertically-disposed filter-beds removable 85 arranged in said casing, means for forcing water under pressure through said filter-beds, a tubular catch-pan arranged at the base of the front face of each filter-bed, and means for flushing said catch-pans. 90

4. In a filtering apparatus, a filter-bed, a tubular catch-pan secured to the base of the front face of said bed, said pan having a peripheral opening adjacent to the face of said bed and an open end, and a drainage-pipe connected with the open end of said catch-pan. 95

5. In a filtering apparatus, a casing interposed in a water-distributing pipe or main, a series of vertically-disposed filter-beds removable 100 arranged in said casing, each of said filter-beds having in its sides flat indentations and at its bottom a wedge-shaped indentation, flat and wedge-shaped ribs arranged respectively at the sides and bottom of said casing 105 adapted to engage the indentations in said filter-beds, and means for forcing water under pressure through said filter-beds. 110

6. In a filtering apparatus, a casing interposed in a water-distributing pipe or main, a series of vertically-disposed filter-beds removable 110 arranged in said casing, each of said filter-beds having in its sides flat indentations and at its bottom a wedge-shaped indentation, flat and wedge-shape ribs arranged respectively at the sides and bottom of said casing, 115 a tubular catch-pan arranged at the base of the front face of each filter-bed, and means for forcing water under pressure through said filter-beds. 120

In testimony whereof I have hereunto set my signature in the presence of two subscribing witnesses.

DANIEL M. PFAUTZ.
